United States Patent Office

Des. 211,827

Patented July 30, 1968

211,827

KEY

Sam Reisner, Pacific Palisades, Calif., assignor to Osco Corporation, a corporation of California

Filed Feb. 2, 1968, Ser. No. 10,418

Term of patent 14 years

(Cl. D50—4)

FIG. 1

FIG. 2

FIG. 3 FIG. 4

FIG. 5

FIG. 6

FIG. 7

FIG. 8

FIG. 9

FIGURE 1 is a side elevational view of a key showing my new design;

FIGURE 2 is an elevational view thereof showing the side opposite to that shown in FIGURE 1;

FIGURE 3 is a front end elevational view thereof;

FIGURE 4 is a rear end elevational view thereof;

FIGURE 5 is a top plan view thereof;

FIGURE 6 is a bottom plan view thereof;

FIGURE 7 is a side elevational view of a key showing a modified embodiment of my design wherein the shanked portion is upside down as compared to the shank portion of FIGURE 1;

FIGURE 8 is a side elevational view of a key showing a third modification of my design wherein the shanked portion of the key is symmetrical about its horizontal longitudinal axis; and,

FIGURE 9 is a front elevational view of the key illustrated in FIGURE 8.

The dotted line showing in FIGURE 1 is for illustrative purposes only.

I claim:

The ornamental design for a key, substantially as shown and described.
